UNITED STATES PATENT OFFICE.

GEORGE P. MACNICHOL, OF TOLEDO, OHIO, ASSIGNOR, BY MESNE ASSIGNMENTS, TO JOHN N. WILLYS, OF TOLEDO, OHIO.

GLASS-CUTTING MECHANISM.

1,298,987.

Specification of Letters Patent.

Patented Apr. 1, 1919.

Application filed April 11, 1914. Serial No. 831,165.

To all whom it may concern:

Be it known that I, GEO. P. MACNICHOL, a citizen of the United States of America, residing at Toledo, Lucas county, Ohio, have ⁵ invented new and useful Glass-Cutting Mechanisms, of which the following is a specification.

This invention relates to cutting and severing mechanism.

10 This invention has utility when embodied in devices for determining definite lengths of material as glass in a quick and accurate manner.

Referring to the drawings:

15 Figure 1 is a plan view with parts broken away of an embodiment of the invention as a gang cutter;

Fig. 2 is a side elevation of the mechanism of Fig. 1;

20 Fig. 3 is a section on an enlarged scale on the line III—III, Fig. 1, looking in the direction of the arrow;

Fig. 4 is a section on the line IV—IV, Fig. 3, looking in the direction of the arrow, ²⁵ showing the heating mechanism only;

Fig. 5 is a section on the line V—V, Fig. 1, looking in the direction of the arrow;

Fig. 6 is a detail in plan of one of the ware progressing sustaining rollers; and

30 Fig. 7 is a side elevation of one of the sectional holders with parts broken away.

Mounted upon the sustaining rod 1 are the boxes or upper section holding elements 2 and the lower hinged holding elements 3. ³⁵ These sections 2, 3, of the holder carry removable bushings 4 which may be of a size to conform to the article or ware being cut. The mechanism is especially designed for handling articles of cylindrical contour as tumblers, lamp chimneys, tubing, etc. The bushings 4 are shown engaging the glass tube 5, Fig. 7. In the handling of certain ware, it is desirable to have the bushings in more than one part or in separate sections, ⁴⁰ say as shown in Fig. 7. To assist in the proper centering or holding of the ware these bushings 4 are shown as provided with stems 5 with which springs 6 coact as compressed by the plugs 7. The adjustment of the plugs 7 serves to determine the force of the gripping action against the ware being handled.

From the source of energy, as generator 8, lines 9, 10, lead to the terminals 11, 12, respectively, in the holder sections 2, 3. As

shown in Fig. 3 there are two sets of bushings 4 in the complete holder 2, 3, said sets being slightly spaced to form an annular groove therebetween. The block 13 adjusted by the screw 14 takes the current from the line 11 and delivers to the hot wire 15 extending to the block 16 on the opposite side of the section 2 from the block 13. With the blocks 2 and 3 against each other the block 16 contacts a similar opposing block 17 to close the circuit from wire 15 to wire 18 connected to the block 19 to which is attached the terminal 12 of the line 10. The circuit is accordingly completed and serves to heat the wires 15, 18, held just outside or away from the ware 5 by the adjustable blocks 13, 19, 16, 17. These heating mechanisms or hot wire half circles 15, 18, also just clear the bushings 4 on each side thereof.

With some kinds of wire 15, 18, and in the handling of certain ware, the device disclosed is sufficient to insure a proper severing. However, as an additional safeguard and of considerable advantage with some sizes of wire a further localizing of the heat zone is to good purpose. This is accomplished by keeping the bushings cool say by circulation of water through the chambers of the holder sections 2, 3. For instance, the supply line 20 has branch 21 leading to the lower part of the chamber of section 2 and discharging by line 22 from the upper part of section 2 into the return line 23. For cooling the lower and relatively movable holder section 3 the flexible duct 24 from the supply line 20 delivers water to the lower part of the chamber of the holder 3, which water is discharged therefrom into the flexible duct 25 leading to the return water line 23. ⁹⁵

In the handling of ware, especially tubing, there may be slight deviations in direction or in diameter. The yieldable bushings 4, to an extent, will care for such deviations. However, as a further check the holder sections 2, 3, have their bushings 26 coacting with the shaft 1 yieldable as determined by the springs 27. These yieldable features have additional utility in the rotation of the ware during heating, which rotation is ¹⁰⁰ desirable in the instances where a straight cut surrounding a cylindrical object is desired. When so handled, the cut or severing is accurate and furthermore there is not a disturbance of the glass away from the cut ¹⁰⁵ ¹¹⁰

the ware and having yieldable gripping members engaging the ware, a cooling fluid circulating system connected with said hollow sections, and a heating element disposed between said gripping members and around the ware.

6. A device of the class described, comprising the combination of a ware holder formed of a plurality of hollow sections adapted to extend circumferentially around the ware and having yieldable gripping members engaging the ware, a cooling fluid circulating system connected with said hollow sections, a heating element disposed between said gripping members and around the ware, and means for rotating the ware within said holder.

7. A device of the class described, comprising the combination of a ware holder, including a plurality of hollow sections adapted to extend circumferentially around the ware and forming fluid circulating chambers, the inner walls of which are provided with cooling extensions projecting radially into said chambers, gripping members between the ware and said sections, and heating means disposed between said gripping members and around the ware.

8. A device of the class described, comprising the combination of a ware holder, including a plurality of hollow sections adapted to extend circumferentially around the ware and forming fluid circulating chambers, the inner walls of which are provided with hollow cooling extensions projecting into said chambers, gripping members between the ware and said sections having stems projecting into the extensions, means

engaging said extensions to hold the gripping members in yielding engagement with said ware, and heating means interposed between said gripping members and around the ware.

9. A device of the class described, comprising a ware holder formed of a plurality of hollow sections adapted to extend circumferentially around the ware, a fluid circulating system connected with said hollow sections, heating mechanism for the ware located between said sections, and means for rotating said ware between said sections.

10. A device of the class described, comprising a ware holder formed of a plurality of yieldingly connected sections adapted to extend circumferentially around the ware and each provided with one or more radial sleeves, gripping members for the ware having stems projecting into said sleeves, and springs yieldingly forcing said gripping members in contact with the ware.

11. A device of the class described, comprising a ware holder formed of a plurality of sections adapted to extend circumferentially around the ware and each provided with one or more radial sleeves, gripping members for the ware having stems projecting into said sleeves, springs yieldingly engaging said stems, means for tensioning said springs, and heating means disposed between said gripping members and around the ware.

In witness whereof I affix my signature in the presence of two witnesses.

GEORGE P. MacNICHOL.
